UNITED STATES PATENT OFFICE.

JOHN FLOYD, OF WASHINGTON, DISTRICT OF COLUMBIA.

SWITCH FOR SUSPENDED ELECTRIC CONDUCTORS.

SPECIFICATION forming part of Letters Patent No. 655,216, dated August 7, 1900.

Application filed December 8, 1899. Serial No. 739,666. (No model.)

To all whom it may concern:

Be it known that I, JOHN FLOYD, a citizen of the United States of America, residing at Washington, in the District of Columbia, have 5 invented certain new and useful Improvements in Switches for Suspended Electric Conductors, of which the following is a specification.

One object of this invention is to provide a 10 switch for suspended electric conductors which will prevent the trolley-wheel from jumping in making turns and crossings regardless of the curves or of the speed of the car, thus avoiding accidents to the main conductor and rendering the trolley-rope of no use except when reversing.

Another object of this invention is, that it makes a continuous circuit certain and will work accurately at all times, either when it 20 is hot or cold or when the car is at its highest or lowest speed, always maintaining its shape and position.

A still further object of this invention is that its cost of manufacture and maintenance 25 is greatly in its favor as regards other devices, for it is exceedingly cheap and simple in its construction, reliable and convenient in use, it does not require a skilled operator to place it in position, and it will efficiently 30 perform all of its intended functions.

For the attainment of the several objects my invention consists, in brief, in certain details of construction, arrangement, and combination of parts, all of which will be more 35 fully described hereinafter and the specific points of novelty of which will be designated in the appended claims.

Before proceeding further into a detailed description of the several auxiliary features 40 of my invention I desire to here distinctly state and emphasize the fact that although I have shown in the accompanying drawings and described in the following specific description certain component and coöperating 45 parts which I deem sufficiently improved and operative to carry out the fundamental principles herein incorporated, however I do not confine myself to the exact details of construction so illustrated and described, since 50 obvious departures may be made without deviating from the inherent and generic features constituting the gist thereof.

Referring to the accompanying drawings, Figure 1 is a perspective view of the main and branching conductors united by my improved switch. Fig. 2 is a plan view. Fig. 3 is an inverted plan view. Fig. 4 is a modification.

Referring by letters to the drawings, A represents the main conductor, and B the branch- 60 ing conductor, adapted to be connected by my improved switch.

The switch is comprised of a single piece of wire formed substantially in the shape of a Y, bent upward at the point C, thence in a 65 curve similar to that of a balloon, the ends D and E being bent or branching from the point F in an oblique position with respect to the stem of the Y. At the top or center of the curve I form each of the ends with a 70 twist G, which strengthens the structure and increases the stiffness.

In Fig. 4 I have shown a modified form of my invention, which consists of a similar structure, merely dispensing with the twist 75 G. This form is employed when a stiff heavy wire, such as the "00," so commonly known, is used.

It will thus be readily seen that there is an upwardly-extending space between the ends 80 of the Y which will permit the ready passage of the flanges on the trolley-wheel in any direction either when running on the main or branch conductor.

Having thus described my invention, what 85 I claim as new, and desire to secure by Letters Patent, is—

1. A switch for electric conductors, comprising a single piece of wire, having arms extending integral therewith, of the wire bent 90 upwardly in a loop, the arms having a twist in the center of the loop and extending obliquely, substantially as shown and described.

2. A switch for electric conductors, comprising a single piece of wire formed substantially in the shape of a Y, said wire bent upwardly in a curve similar to that of a balloon, its ends being bent oblique with respect to the stem of the Y, of a twist in the center of the curve, substantially as shown and de- 100 scribed.

3. A switch for electric conductors, comprising a single piece of wire, having arms extending integral therewith and flaring ob-

liquely therefrom, a portion of the wire and arms bent upwardly in a loop, and having a twist in the center of said loop, substantially as shown and described.

5 4. A switch for electric conductors, comprising a single piece of wire, bent upwardly and provided with integral arms flaring obliquely therefrom, each arm forming a loop,

substantially as shown and for the purpose set forth.

In testimony whereof I have hereunto set my hand this 5th day of December, 1899.

JOHN FLOYD.
